(54) **BOOTS & SHOES, MANUFACTURING**

(76) Inventor: **Samuel Chamberlain**

The Schedule referred to in these Letters Patent
is making part of the same, containing a Description
in the Words of the said Samuel Chamberlain him-
self of his State of the Art.

The invention of this improvement in Boots &c. has
called the Water proof Shoe, consists in the application of
an additional inner sole of cork saturated with melted
tallow & tis way, or with linseed oil which is preferable,
or of that thick woollen cloth, or any other suitable sub-
stance put on the inside of the common inner sole, with
a cover of thin leather or cloth carried round the edges of
the common inner sole, & sewed with the rest to said inner
sole, so that the said additional inner sole of cork &c. is
by said covering kept firmly in its place. The common
inner sole is between this additional sole, & the outer sole.

This additional inner sole being made of elastic substance
covered with thin leather or cloth forms a very agreeable sur-
face for the foot, & at the same time keeps the water from
penetrating thru' to the foot. Between the lining & the up-
per leather of the shoe a piece of bladder cut in the shape of
the upper leather, is put, which will prevent the water from
soaking thru' the upper leather, so as to wet the foot. To
prevent the water from getting into the shoe at the top of the
vamp, where it is laced or tied, a cap of a proper size & shape
of leather is sewed on to the vamp so as to cover the lacing
of the shoe. The cover of said cap is not sewed to the vamp
but is left so as to turn over in order to lace up the shoe.

This cover of said cap is fastened to the vamp of the
shoe by a clasp or buckle or by a string. Shoes made with
these improvements will keep the feet dry & comfortable &
are very easy for the feet. Tanass or even birch bark put

between the outside & common inner soles of shoes will also give further security against the bad effects of water.

Bladder put between the said additional inner sole & the common inner sole, or between the common inner sole & the outside sole, when the said additional inner sole is not used, has a good effect in keeping the water from soaking thro' to the sole. Men's shoes as well as men's shoes & boots may be made with any or all of these improvements, the only exception in Boots, & at the same time will be as good in appearance as they are comfortable, warm & dry. Children's shoes made with the above improvements will be found to tend very much to the preservation of their health; as well as to the health of every person of mature age who wears them.
